UNITED STATES PATENT OFFICE.

WILLIAM BUNTING, OF BROOKLINE, MASSACHUSETTS.

LAVATORY APPARATUS.

1,150,098.

Specification of Letters Patent.

Patented Aug. 17, 1915.

Application filed January 30, 1913. Serial No. 745,089.

To all whom it may concern:

Be it known that I, WILLIAM BUNTING, a citizen of the United States, residing at Brookline, in the county of Norfolk and 5 State of Massachusetts, have invented an Improvement in Lavatory Apparatus, of which the following is a specification.

This invention relates to certain improvements in lavatory apparatus, and particularly that especially designed for use in connection with lavatory basins in surgical rooms, where it is desired to wash the hands without touching any apparatus, although the apparatus herein described is also advantageous when used in other relations.

The use of liquid soap in surgical lavatories is particularly desirable, but the receptacle in which it is usually contained must be touched by the hand, in order to secure a portion of the contents thereof, which is a particularly objectionable feature in this relation.

The object of my invention is to provide a lavatory basin with means whereby any 25 desired quantity of liquid soap may be discharged at a convenient point without touching the hands or arms to the apparatus, and to provide means whereby water may also be discharged in the same manner, so that 30 one may wash his hands with soap and water without touching the apparatus, and may have free use of his hands and arms while he is doing this.

I accomplish these objects by the means 35 shown in the accompanying drawing, in which,

Figure 1 is a side elevation of a basin provided with a delivering apparatus made according to my invention. Fig. 2 is a sectional view taken at the line 2—2 of Fig. 3. Fig. 3 is a plan view of the apparatus. Fig. 4 is a sectional view taken at the line 4—4 of Fig. 1. Fig. 5 is a rear elevation of the apparatus. Fig. 6 is a detail sectional view 45 of the soap pump.

In the drawing *a* indicates an ordinary set basin having the usual horizontally projecting rim or slab, said basin being supported upon a pair of horizontally disposed, 50 tubular brackets, *b*, *c*, said brackets being mounted at their rear ends on the wall *d*, in the rear of the basin, and extending therefrom beneath the rim in parallelism at opposite sides of the bowl, adjusting screws 55 being provided between the upper sides of

the brackets and the under side of the basin rim.

Said brackets *b*, *c*, are respectively provided at their front ends with right angularly shaped, oppositely disposed lugs *e*, *e'*, 60 and bell-crank levers *f*, *f'* are pivotally mounted on the ends of said lugs, an arm of each lever extending forwardly beyond the front edge of the basin rim, or front outline thereof, and approximately perpendicularly thereto. Said levers are arranged to swing horizontally away from each other and are connected to operating rods *g*, *g'*, which are reciprocally mounted within the brackets *b*, *c*, so that as said levers are 70 pushed laterally outward from the middle of the bowl, said rods will be pushed inwardly, or rearwardly.

The forwardly projecting arms of said levers *f*, *f'*, are provided with vertically 75 arranged flattened end portions, which are held at such a height that the user may conveniently press the hip or the side of the leg between the knee and the hip, against either lever as he stands between them in 80 front of the bowl.

Bell-crank levers, *i*, *i'*, are respectively mounted on lugs *k*, *k'* secured to the brackets *b*, *c*, in the rear of the wall *d*, one arm of each lever being held in engagement with its 85 corresponding rod *g* or *g'*, as shown in Fig. 4. The lever *i* is connected, by a link *j*, to one arm of a bell-crank lever *l*, mounted on a bracket *m*, supported on a pump cylinder *n*. 90

A closed receptacle *o*, for liquid soap, is connected by a pipe *o'* to the cylinder *n*, said pipe being supported by a suitable bracket *p* on the rear side of the wall, which also provides a support for the pump cylinder *n* and the receptacle *o*. 95

A plunger *n'* is mounted in the cylinder *n* and is held in operative engagement with the opposite arm of the bell-crank lever *l* to that which is connected to the link *j*, so that, 100 when said lever *l* is swung, said plunger may be reciprocated, and by providing an adjustable connection between the lever *l* and link *j* the length of the stroke of the piston may be varied.

A spring *h* is provided in the cylinder *n* which is arranged to engage the plunger *n'* to return the parts to initial position.

Check-valves *q*, *q'* are respectively provided in the pipe *o'* and a discharge pipe 110

n^2 which leads from the pump cylinder, so that, as said plunger n' is reciprocated, the liquid may be drawn from the receptacle o and discharged through the pipe n^2 .

5 The bell-crank lever i' is connected to a link r , which is in turn connected to the operating-lever s , of a water supply valve t , of the self-closing type.

A discharge pipe u is mounted in the wall 10 d , within a casing x and is connected at its rear end to the discharge port of the water supply valve t , by a pipe t' , and at its front end to a depending spray nozzle y , which is held over the middle of the basin, so that, 15 when the valve t is opened, water will be discharged from the nozzle, the latter being held in such a position that the hands may be conveniently held thereunder.

The discharge pipe n^2 from the pump n , 20 is connected to a pipe v which extends through a packed joint and coupling into pipe u and through said pipe u and the nozzle y , and terminates at its outer end a short distance beyond the end thereof, said 25 nozzle being preferably provided with a spray strainer z in its end in the middle of which the pipe v is supported. The pipe v is of small diameter and has a depending end portion corresponding to the depending 30 nozzle y , so that, when said pipe is filled with liquid, air cannot pass the liquid therein, which will be retained by air pressure.

With the above described apparatus, when 35 the lever f is pushed outwardly, the pump plunger will be raised, so as to force a supply of soap into the discharge pipe n^2 , and after this operation has been repeated a number of times, the pipes connected to the pipe n^2 will become completely filled with the 40 liquid soap, so that each time the lever f is operated a measured quantity of liquid soap will be discharged from the pipe v . As the receptacle o is arranged below the level of the discharge end of pipe v , there will be no 45 leakage of the soap from the receptacle through the pipe, and soap will only be discharged when the pump is operated.

The user will, ordinarily, hold his hands 50 beneath the discharge pipe and first operate the lever f to discharge a supply of soap onto his hands, and then will push against the lever f' and open the supply valve, so that then water will be discharged onto his hands from the nozzle.

55 The particular form of valve t which is used is not material, that is, either a single valve controlling a single water supply may be employed, or a compound valve controlling both a hot and cold water supply may 60 be provided, the type which I preferably employ being one which will first turn on the cold water and then gradually turn on the hot water and shut off the cold water, as the lever is pushed in one direction.

65 It will be apparent that, with the above

described apparatus, the user may wash his hands with soap and water without touching any apparatus and at the same time may also have free use of his hands and arms.

It will also be apparent that, with the above described apparatus, all the apparatus is concealed except that which must necessarily be exposed, namely, the operating-levers and the single discharge pipe for the water and soap, so that, the whole device will have an attractive and ornamental appearance and a minimum amount of surface will be exposed which must be kept clean.

I claim:—

1. A dispensing apparatus for a lavatory basin comprising, an operating lever adapted to be arranged at the front thereof, and normally to be held in position to be pushed aside by the body of the user, a pump connected to said lever, a liquid soap receptacle connected to the intake of the pump, a discharge pipe connected to the discharge of the pump and adapted to extend over the basin to deliver the soap thereto when the lever is moved in one direction, and means to return the lever to its normal position, substantially as described.

2. In combination with a lavatory basin, a water supply pipe arranged to discharge into said basin and having a valve therein, an auxiliary pipe having its discharge end adjacent the discharge end of said supply pipe, a liquid soap dispensing apparatus connected to said auxiliary pipe, and a pair of levers respectively arranged to operate said valve and said dispensing apparatus to deliver soap and water successively to the basin, substantially as described.

3. In combination with a lavatory basin, a water supply pipe arranged to discharge into said basin, and having a valve therein, an auxiliary pipe arranged within said discharge pipe and terminating adjacent the end thereof, a liquid soap dispensing apparatus connected to said auxiliary pipe, and means to operate said apparatus, and said valve to deliver the soap and water to the basin, substantially as described.

4. A dispensing apparatus for a lavatory basin comprising, a delivery pipe leading thereto above the level of the basin and having a depending pipe of small diameter, at its discharge end, adapted to prevent the passage of air to permit the displacement of liquid therein, a liquid soap receptacle arranged below the discharge end of said pipe, a pump connecting said receptacle and said pipe, and means for operating said pump, substantially as described.

5. A dispensing apparatus for a lavatory basin comprising, a liquid soap receptacle, a pump connected thereto, a delivery tube leading from said pump and adapted to terminate over the basin, a horizontally movable operating lever adapted to be ar-

ranged beneath the basin rim and normally project beyond the front outline thereof in position to be pushed aside by the body of the user, and connections between said lever 5 and said pump to operate the same when the lever is moved from its normal position, substantially as described.

6. In combination with a lavatory basin, a horizontally disposed, tubular bracket 10 mounted at its rear end and extending forwardly at one side of the basin, an operating-rod reciprocally mounted in said bracket, operating means mounted on the front end of said bracket and in engagement with said rod, said operating means being arranged adjacent the front of the basin in position to be moved by the body of the user, to reciprocate said rod, a pipe leading to said basin, having liquid dispensing means 15 connected thereto, and means controlled by said rod when it is reciprocated to operate said dispensing means, substantially as described.

7. In combination with a lavatory basin, 25 a horizontally disposed, tubular bracket mounted at its rear end and extending forwardly at one side of the basin, an operating rod reciprocally mounted in said bracket, a lever mounted on the front end 30 of said bracket and in engagement with said rod, said lever having an arm arranged adjacent the front of the basin in position to

be moved aside by the body of the user, to reciprocate said rod, a pipe leading to said basin, having liquid dispensing means connected thereto, and means respectively controlled by said rod when it is reciprocated by said lever to operate said dispensing means, substantially as described.

8. In combination with a lavatory basin, 40 a pair of horizontally disposed tubular brackets mounted at their rear ends and extending at each side of the basin to support the same, operating rods extending through said brackets and reciprocally mounted 45 therein, a pair of levers mounted therein, a pair of levers mounted to swing on the outer ends of said brackets each lever being arranged to engage its corresponding rod and extending in position to be pushed aside 50 by the lower portion of the body of the user to reciprocate said rods, a pair of pipes leading to the basin having liquid dispensing means connected thereto and means respectively controlled by said rods, when 55 they are reciprocated, for operating said dispensing means, substantially as described.

In testimony whereof, I have signed my name to this specification, in the presence of two subscribing witnesses.

WILLIAM BUNTING.
